UNITED STATES PATENT OFFICE.

MALCOLM A. MURRAY, OF MOUNTAIN IRON, MINNESOTA.

BOAT-PROPELLING MECHANISM.

1,150,292.

Specification of Letters Patent. Patented Aug. 17, 1915.

Application filed October 9, 1913. Serial No. 794,231.

To all whom it may concern:

Be it known that I, MALCOLM A. MURRAY, a citizen of the United States, residing at Mountain Iron, in the county of St. Louis 5 and State of Minnesota, have invented certain new and useful Improvements in Boat-Propelling Mechanism, of which the following is a specification.

This invention relates to boat propelling mechanism, having for its primary object 10 to provide a device which may be associated with an ordinary boat now in use, and which will retain the use of the ordinary oar thereby reducing the cost of manufacture to a minimum.

Another object of this invention is to connect a plurality of oars to the sides of a boat, by means of a universal joint or coupling and to associate with the oars, a simple and efficient actuating means, by means 20 of which the oars on each side of the boat will be simultaneously actuated.

Other objects as well as the nature, characteristic features and scope of my invention will be more readily understood from 25 the following description taken in connection with the accompanying drawings and pointed out in the claims forming a part of this specification.

Referring to the drawing: Figure 1 is a 30 plan view of the device constructed in accordance with my invention illustrating the application thereof:—Fig. 2 is a cross sectional view taken on the line 2—2 of Fig. 35 1 and looking in the direction indicated by the arrows; Fig. 3 is a cross sectional view taken on the line 3—3 of Fig. 1; and Fig. 4 is a top plan view of the device showing the 40 position taken by the oars when pressure is exerted on the actuating lever.

In the drawings wherein is illustrated the preferred embodiment of this invention, in order to properly illustrate the same, a boat 5 is provided which may be of the ordinary or any desired form and having 45 connected to each side thereof a substantially V-shaped bracket 6, the free end of each of the arms thereof being fixedly secured to the outer face of the boat through 50 the medium of rivets or the like, while the V is pivotally mounted at its apex to a connecting bar 7, said connecting bar having the one end thereof bifurcated and pivotally connected to an ear which is appropriately 55 formed on a horizontal bar 8, the latter being arranged in spaced relation to the side

of the boat. The opposite end of said connecting bars 7 is reduced as indicated at 9 for a purpose which will be presently described.

Arranged in uniformly spaced apart relation on each side of the boat 5, are a plurality of sockets 10 each of which is in engagement with the one end 11 of an oar 12, said end 11 being provided with a ball on 60 the terminal thereof for engagement in said socket so as to provide a universal coupling or joint in order to allow for the free movement of the oar. The opposite end of each of said oars is of the ordinary construction 65 with a paddle 13 formed thereon for an obvious purpose. Extending upwardly from said bar 8 are a plurality of arcuate arms 14, the free end of each of which is bifurcated and adapted for pivotal engagement 70 with the one end 15 of each of the pins 16, the latter being counter-sunk in each of the oars 12 having engagement therethrough, said end 15 being enlarged and relatively 75 flat so as to be accommodated between the branches of the bifurcation. By the provision of the pins 16, it is seen that the oars 12 are free to move from engagement with the arcuate arms 14 as indicated by the dotted lines in Fig. 3.

In order to actuate each series of oars on each side of the boat 5, I have provided a simple and efficient actuating lever 17 which in the present instance comprises an elongated rod, the one end of which has 80 formed therein a slot 18 which is engaged by the reduced end 9 of the connecting bar 7, an intermediate portion thereof being pivotally mounted on the side of the boat as indicated at 19 and the extreme opposite end 85 20 thereof being reduced so as to provide a handle for facilitating the actuation of said lever. If desired, a wear plate 21 may be secured to each side of the boat, adjacent the pivot point with which the actuating lever 100 17 is engaged.

In operation, when pressure is exerted on the handle ends 20 of the actuating lever 17, in a forward direction, and the blade ends 105 13 of the oars 12 are allowed to be embedded in the water, it is obvious that the boat will be advanced, in view of the fact that the one end of the lever 17 is in connection with the horizontal bar 8, the latter having engagement with each of the oars 12 through the medium of the arms 14. At the 110 end of the stroke, pressure is exerted rear-

wardly on the handle end of each of the actuating levers 17 which causes the oars to feather owing to their pivotal connection to the bracket 14 and the oars again are allowed to drop into the water and the same operation performed. During this operation, it will be necessary for the oars 12 to have a certain amount of play in order to facilitate the operation of the same, and with this in view, I have provided the universal joints by which the one end of each of the oars is connected to the boat, and the pins 16 by means of which each of the oars 12 are connected to the horizontal bar 8.

15 It will be understood that the above description and accompanying drawings comprehend only the general and preferred embodiment of my invention and that various minor changes in details of construction, 20 proportion and arrangement of the parts, may be made within the scope of the appended claims and without sacrificing any of the advantages of my invention.

Having thus fully described my invention, 25 what I claim as new and desire to secure by Letters Patent is:—

1. A boat propelling mechanism including a plurality of oars, the one end of each of which is pivotally mounted on the sides of the boat, a horizontal bar connecting each of said oars together on each side of the boat, and means forming said connections between said oars and said bar to permit feathering of the former.

35 2. A boat propelling mechanism including a plurality of oars, the one end of each of which is pivotally mounted on the sides of the boat, a horizontal bar connecting each of said oars together on each side of the boat, and arms formed on said bar to pivotally mount said oars to permit of their being automatically feathered.

45 3. A boat propelling mechanism including a plurality of oars, the one end of each of which is pivotally mounted on the sides of the boat, a horizontal bar to connect the oars of each side, arms formed on each of said bars to permit lateral movement of said oars in one direction and to check such 50 movement in the opposite direction, and means for actuating said bars.

55 4. A boat propelling mechanism including a plurality of oars, the one end of each of which is pivotally mounted on the sides of the boat, a horizontal bar connecting each of said oars together on each side of the boat, and an actuating lever pivotally

mounted on each side of the boat and having connection with said horizontal bar for simultaneously actuating the series of oars 60 on each side of the boat.

5. A boat propelling mechanism including a plurality of oars, the one end of each of which is pivotally mounted on the sides of the boat, a horizontal bar, arms carried by said bar and having engagement with said oars, a connecting bar extending from said horizontal bar, and an actuating lever pivotally mounted on each side of said boat, and having engagement with said connecting 70 bar, for simultaneously actuating said oars.

6. A boat propelling mechanism including a plurality of oars, the one end of each of which is pivotally mounted on the sides 75 of the boat, a horizontal bar arranged subjacent said oars, a plurality of arcuate arms carried by said bar and having pivotal engagement with said oars, a connecting bar pivotally mounted on said horizontal bar 80 and having pivotal engagement with the sides of the boat, and an actuating lever pivotally mounted on said boat and having engagement with said connecting bar for the purpose specified.

85 7. A boat propelling mechanism including a plurality of oars, the one end of each of which is pivotally mounted on the boat, a horizontal bar arranged subjacent said oars, a plurality of arcuate arms arranged 90 in uniformly spaced apart relation on said bar, and having engagement with said oars, a plurality of pivot pins, one of which has the one end thereof engaged with each of said oars and the opposite end pivotally engaged to one of said arms, a connecting bar, the one end of which is pivotally mounted on said horizontal bar, the opposite end thereof being reduced, a V-shaped brace interposed between said connecting 100 bar and said boat, said V-brace having pivotal connection at its apex to said connecting bar, and an actuating lever pivotally mounted on each side of the boat and having connection with said connecting bar for 105 simultaneously actuating the series of oars on each side of the boat.

In testimony whereof I affix my signature in presence of two witnesses.

MALCOLM A. MURRAY.
